UNITED STATES PATENT OFFICE.

CHARLES V. HADJEFF AND BERNARD J. BOLDA, OF PORTLAND, OREGON.

DRAFT CONTROL.

Application filed January 27, 1926. Serial No. 84,078.

The object of our invention is to provide means within the fire box of domestic heating units and heat and steam generating plants of a more efficient thermodynamic condition within the fire box.

Still further objects of our invention consist in confining the heat zone of greatest intensity within the central part of the fire box and of the fuel being consumed for heat generating purposes.

Still further objects of our invention is to prevent the admission of cold air entering the fire box around the edges of the fire and to cool the heated air that has been heated by the same passing through the fire.

Additional advantages of our invention consist in the placing around the outer edge of the fire box and between the ends of the grates and the inner shell of the fire box of a compressible fire resistant material that will compensate for the expansion and contraction of the grates and at the same time will prevent the free passage of the air therethrough.

Additional advantages consist in providing an air chamber through which the incoming air to be admitted into the fire box will be preheated before the entrance of the same into the fire box.

Additional advantages consist in providing ventilating holes being placed through the support for the fire grates to aid in the control of the direction of flow of the incoming air and at the same time to preheat the same and to provide the admission of the same over an area of some magnitude.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a side elevation partially in section of a vertical type boiler, illustrating one of our devices in place within the fire box.

Fig. 2 is a perspective, side elevation of one of the circular supports upon which the grates set, adapted for disposition within the fire box, wherein the fire box is circular in form.

Fig. 3 is a perspective view of a part of

one of the grate supports, illustrating the grate in place upon the support and the material disposed between the grate and the shell of the fire box.

Fig. 4 is a fragmentary enlarged sectional view of one of our new and improved devices in place within the fire box, and illustrating the noncombustible, compressible material, disposed between the grate section and shell of the fire box.

Fig. 5 is a perspective, end elevation, in section of a preferred form of the compressible material to be placed between the grate and the shell of the fire box.

Fig. 6 is a perspective view, of a form of the support, as adapted to a fire box of the rectangular form.

Like reference characters refer to like parts throughout the several views.

1 is the shell of a boiler, having a fire box 2, disposed therein and having vertical flues 3, for the passage of the heated gases and the products of combustion therethrough, around which the medium to be heated is placed. Brackets 4, are placed within the fire box and are secured to the shell of the boiler by suitable fastening means, as rivets 5, and having a right angle support 6, formed on the upper end thereof, upon which the support 7, is secured. This support in a circular form of fire box would preferably be made of more than one section. The support 7, rests on its lower side 8, directly upon the bracket support 6, and is placed in close proximity about its outer periphery, to the inner shell of the fire box, the same is preferably formed in two sections, a lower section 8, and the upper section 9, and having webs 10, disposed therebetween to maintain the upper and lower section in spaced relationship. Free air passage openings 11, are disposed around the outer periphery of the outer section, through which the free air may be permitted to pass. The free air passes between the upper and lower section and thence through the openings 11 disposed in the upper section.

Disposed upon the upper section 9 of the support is placed the grate bar sections 12; the grate bars are preferably made somewhat smaller in diameter than the inner diameter of the fire box, leaving a space therebetween, as shown at 13. This space is variable, depending upon the relative temperatures of the grate section and that of the

shell of the fire box; as it will be apparent that if the grate section is heated to a fairly high temperature, the same will expand and if the fire box shell is of a fairly low temperature the same will be somewhat smaller in diameter than if heated to a high temperature. Through the space 13, which is a variable one, free air normally passes. To prevent the passage of free air therebetween and to compensate for the variableness of the space, we have provided a noncombustible flexible material member 14, which we have found gives best results as and when made of a flexible material. The side reinforcing walls are preferably made of mesh material having vertical and longitudinal section members and between which we place noncombustible material while in a plastic state, as asbestos, or other material that remains in a compressible state, while at high temperature and yet in a somewhat porous condition, as is obtained in asbestos products or other similar noncombustible mineral products, this is shown at 15, and is preferably placed therein while in a plastic state. This is formed wedge shaped and is disposed around the end grate section and between the same and the fire box wall and rests directly upon the upper section of the supporting member 9, and directly above the opening 11, provided for the passage of free air therebetween. The spaced relationship existing between the lower support member 8, and the upper support member 9, permits of the passage of the air therebetween, thus warming the same and the partial prevention of the free passage of the air through the action of the disposition of the compressible member 14, between the ends of the grates and the side walls of the fire box retards the free passage is further retarded due to the opening 11 within the upper support member, while maintaining a state of equilibrium or partial equilibrium between the air disposed below and there above has a tendency of retarding the draft and thus forcing the air to enter through the grate section and through the combustible material placed thereupon to be used for the generation of heat.

This same form of compressible material that is noncombustible, may be placed within any form of fire box, whether the same is used in a domestic cooking stove where hard fuel is used, or within the fire box of a stationary steam generating plant, or within the fire box of a locomotive type boiler fire box and it is immaterial whether the fire box is circular in construction, or whether the same is rectangular in form.

While the form of mechanism herein shown and described is admirably adapted to fulfill the objects primarily stated, it is to be understood that it is not intended to confine the invention to the one form of em-

bodiment herein shown and described, as it is susceptible of embodiment in various forms, all coming within the scope of the claims which follow.

What we claim is:—

1. In a draft control, the combination of a fire box, of a bracket disposed within the fire box, a support disposed upon the bracket composed of an upper and a lower section spaced apart with openings disposed about 75 the outer periphery of the upper section, grates disposed upon said support and having the edges thereof spaced apart from the inner wall of the fire box, and a noncombustible filler disposed between the edges 80 of said grates to be placed upon the support and the inner wall of the fire box, and resting upon the upper section of said support.

2. In a draft control, the combination of a fire box, of a supporting member disposed 85 within the fire box, composed of an upper and a lower supporting member spaced apart, air ports disposed upon the outer periphery of the upper supporting member, fire grates placed upon the support and spaced from the inner wall of the fire box and a compressible noncombustible filler member disposed between the grate and the inner wall of the fire box and placed above the ports of the upper member.

3. In a draft control, the combination of a fire box, of a supporting member disposed in a horizontal position within the fire box, bracket supports secured to the inner wall of the fire box and adapted to maintain the support in a fixed position, the supporting member composed of an upper and lower section and spaced apart by webs, grate bars disposed upon the upper supporting section and spaced apart from the inner fire box wall, openings disposed through the upper support and connecting the space between the lower and upper support and adapted to discharge free air in the space between the grates and the inner fire box wall and a wedge shaped noncombustible compressible member disposed between the inner fire box wall and the ends of the grate bars and immediately above the openings for the passage of free air.

4. In a draft control, the combination of a fire box, of a grate supporting member having free air passages disposed therethrough adjacent the outer periphery of the grate support disposed within the fire box, grates disposed upon the grate support and spaced apart from the inner wall of the fire box, and a reinforced compressible, noncombustible member disposed between the grates and the inner wall of the fire box and being disposed above the free air passages through the grate support.

5. In a draft control, the combination of a fire box, of a grate supporting member composed of an upper and a lower section

spaced apart and having free air passages adjacent the outer edges of the upper section and passing therethrough, brackets secured within the fire box and adapted to maintain the grate supports in fixed position, grates disposed upon the grate supports and spaced apart from the inner walls of the fire box, and a reinforced compressi-

ble, noncombustible member disposed between the ends of the grates and the inner walls of the fire box and above the free air passages disposed through the upper section of the grate supports. 10
